LOCK FOR WOODEN CASKET CASES

John A. Putman, Laurens, S. C.

Application September 7, 1938, Serial No. 228,831

3 Claims. (Cl. 292—80)

The object of this invention is to provide an improved lock or latch adapted to lock the tops of coffin or casket cases to the bodies of such cases. At the present time, it is the practice to 5 secure the tops of these cases in position with screws. This renders it necessary for the person putting the top in place to get down into the grave.

It is a primary object of the present invention 10 to provide a latch which will permit the placing of the top in position without the necessity of anyone's entering the grave. To secure this result, I provide a case-carried latch with which 15 the top may be engaged by lowering the top with cords or ropes, the lock embodying spring detents with which the top is adapted to engage.

I am aware of the fact that it is common to 20 provide snap fastenings for many different types of objects. However, the lock of the present invention is intended to meet the special conditions met with in the undertaking profession. Among 25 the features which are essential in the provision of a lock of the character of that with which we are here concerned are the following:

25 First, the structure must be so designed as to project above the body of the case a sufficient distance to constitute a guide for the lid as the latter is being lowered into position;

Second, because it is used upon ordinary cheap 30 wooden cases, it must be capable of being stamped from a single piece of sheet metal; and

Third, despite the fact that it is stamped from a single piece of sheet metal, it must have such 35 inherent stiffness that it will not yield to an undue extent laterally, i. e., it must be stiff enough and strong enough so that as the top is lowered into place, the spring of the lock will yield to let the top pass by but not the whole lock.

In the accompanying drawing, wherein like 40 numerals designate corresponding parts throughout the several views:

Figure 1 is a view in side elevation of one end of a casket case, showing one of the locks applied thereto;

Fig. 2 is a plan view of one of the locks, and

Fig. 3 is a vertical sectional view upon line 3—3 of Fig. 1, upon an enlarged scale.

In the drawing, 5 designates the body of the casket case and 6 the lid thereof. The locks of the present invention may be in any desired number, but there should be at least four of them, one adjacent each corner of the casket case. Each lock is formed of a single piece of sheet metal 7. The opposite sides of this sheet 55 of metal are bent or rolled to tubular form, as

indicated at 8, these tubes constituting stiff side standards, by virtue of which the necessary rigidity and resistance to lateral yielding is provided.

The sheet of metal is cut vertically along the 5 insides of the tubes, as indicated at 9, so that the lower portion of the sheet of metal is separated from the tubes, and this separated portion is bent up into the form of a spring tongue 10, a downwardly facing shoulder 11, and a vertical 10 apron 12. The upper edge of the structure is preferably beveled or swaged over outwardly as indicated at 13 to aid in guiding the lid 6 into place.

Before the case 5 is lowered into the grave, the 15 locks are secured rigidly to the side walls thereof by screws, bolts or other suitable fastening devices, indicated at 14, which pass through the lower portions of the standards 8 and engage the 20 side walls of the case.

It is clear that when the relatively heavy lid 25 6 is lowered and is permitted to fall with a sharp blow upon the inclined surface 10a of the spring section 10, said spring section will give outwardly and permit the edge of the top to snap thereby. 30 The downwardly facing shoulder will then engage over the upper face of the lid and hold the same securely in place. The apron 12 will engage the outer edge of the lid.

The use of this device provides a structure 35 much more resistant to the attempts of any person to tamper with a casket after it has been placed in the grave than would be the case where ordinary screws were used, because after the top has once been placed in position, it cannot be removed unless all four of the springs are pressed outwardly at the same time. This would require 40 at least two persons to enter the grave, and even then such persons would have to stand upon the top of the casket case, and they could not simultaneously disengage the springs and raise the casket top, because of their own weight.

Furthermore, the arrangement shown lends itself very readily to being positively locked to prevent the despoiling of the grave by thieves or 45 other ill-disposed persons, because it would be a simple matter to fill the space behind the spring tongue 10 with hydraulic or Portland cement, letting such cement engage in the openings 50 of the tubular members 8.

After such cement had hardened, it would not be possible for the spring tongue 10 to be pressed outwardly. It would be difficult to remove the cement, because the tubular members would lie close to the side of the grave, and the spring 55

tongue itself would protect the cement from attack from the front.

It is to be understood that the invention is not limited to the precise construction set forth, but that it includes within its purview whatever changes fairly come within either the terms or the spirit of the appended claims.

Having described my invention, what I claim is:

- 10 1. A lock for a casket case comprising a conventional body portion and lid, said lock consisting of a single sheet of material provided at its edges with vertical tubular members and having its intermediate portion separated from said tubular members throughout a portion of the height of such tubular members to thereby separate the lower central portion of such piece of

material from said tubular members, said lower central portion comprising an inwardly directed spring tongue presenting an inclined inner face over which the edge of the lid is adapted to ride as said lid moves downwardly, to thereby deflect 5 the spring tongue outwardly to permit the lid to pass thereby.

2. A structure as recited in claim 1, wherein said spring tongue terminates in a downwardly directed apron which lies against the outer edge 10 of the lid when said lid is in place.

3. A structure as recited in claim 1, wherein the metal of the lock is beveled outwardly at its top edge to constitute a guide for the lid when said lid is being lowered.

JOHN A. PUTMAN.
